UNITED STATES PATENT OFFICE.

WILLIAM HENRY MORGAN, OF ALLIANCE, OHIO.

METHOD AND APPARATUS FOR SHAPING HOT-METAL BLANKS.

1,414,660.

Specification of Letters Patent. Patented May 2, 1922.

Application filed June 13, 1919. Serial No. 303,874.

To all whom it may concern:

Be it known that I, WILLIAM H. MORGAN, a citizen of the United States, and a resident of Alliance, in the county of Stark and 5 State of Ohio, have invented certain new and useful Improvements in Methods and Apparatus for Shaping Hot-Metal Blanks; and I do hereby declare the following to be a full, clear, and exact description of the invention, such as will enable others skilled 10 in the art to which it appertains to make and use the same.

My invention relates to an improvement in method and apparatus for shaping hot 15 metal and particularly for shaping car wheels and car wheel tires, and it consists broadly in expanding a hot or semi-plastic blank, reducing its cross sectional area and shaping its outer face by centrifugal action 20 in a rotating die or mold.

In the accompanying drawing Figure 1 is a view in vertical section of an apparatus embodying my invention. Figure 2 is a view in horizontal section taken through 25 the bearings of shaft 27 and showing one half of the apparatus. Figure 3 is a fragmentary section of the table or disk, the cover 14 and the blank after it has been shaped and Figure 4 is a view in section 30 through the blank and table.

The main frame 1 of the machine is approximately conical in shape and is provided with bearings for the moving parts. 2 is a cap resting on the top flange 3 of the main 35 frame 1 and provided with lugs 4 by which it may be removed and replaced on the frame 1, and with a peripheral flange 5 overhanging the edge of the top flange 3 for holding the cap solidly in position over the work.

6 is the main vertical spindle or shaft located symmetrical with the main axis of frame 1, and mounted at its lower end in the ball bearing 7 carried in bearing 8 at the bottom of main frame 1, and in bearing 9 40 adjacent to the upper end of said main frame. Securely keyed to the upper end of spindle or shaft 6 is the table or disk 10, which is provided on its upper surface with grooves 11, which radiate from the axis of the disk, and gradually widen so that they are somewhat wider at their outer ends than they are at their inner ends, and both ends of the groove are preferably curved or inclined so as to gradually merge into the surface of the disk. The function of these 45 50 55 grooves is to engage radial lugs 12 on the

blank 13 to be manipulated so as to positively cause the blank to rotate with the disk 10, and also for holding it centrally with relation to the disk. This disk is provided 60 at its outer edge with an upwardly projecting flange 10^a the inner face of which is finished in the form of the outer face of a wheel tire or other article to be shaped.

Removably secured to the disk 10 by bayonet joint, is the cover 14 preferably provided with a central opening the diameter of which is slightly greater than the diameter of the blank 13 so that the latter may be passed through the opening onto the disk, 70 and provided with holes 15 for the insertion of bars or rods for manipulating and handling it. This cover 14 serves to guide the blank being manipulated and operates to prevent it from flying out of the die or mold 75 when the latter, which is composed of the disk 10 and cover 14, is rotating at a high rate of speed.

When it is desired to stop the rotation of the disk after the power has been withdrawn, the plungers 18 only one being shown are elevated, thus carrying the brake block 19 into contact with the under face of the disk, which lift the latter slightly and operate by their frictional contact to quickly 85 bring the disk to a stop. The plungers 18 are each mounted in a cylinder 20 to which pressure, water or air, is supplied through the pipe 21. Instead of making the brake blocks 19 separate, they may be connected 90 in the form of a ring as shown in the drawing, which would be evenly lifted by the several plungers 18.

Cut on the lower portion of spindle or shaft 6 is the pinion 22, which is driven by 95 gear 23 keyed to shaft 24, which latter is mounted in bearings 25 and 26 preferably integral with frame 1. At the upper end of shaft 24 and above bearing 26, is the mitre gear 26^a which is engaged by a mitre gear on the driven shaft 27, which latter is journaled in bearings carried by frame 1 and is provided with a drive pulley operated by a belt from a suitable source of power.

The whole machine is movably supported 105 on the balls 28 carried by the base ring 29, and is held down on the base by the plates 30, which are mounted at their ends on the bolts 31 and are yieldingly held against the frame 1 by the springs 32, washers 33 and 110 nuts 34, so as to allow of a slight oscillation of the whole of frame 1 with reference

to the base ring 29, due to the high revolving speed of shaft 6 and the parts carried by the latter.

The machine shown was designed for a speed of approximately four thousand revolutions per minute for forming thirty-three inch diameter tires. The blanks are heated to a forging temperature and the temperature of the blank would determine the speed necessary to form the tire. If the blank be heated above a temperature say two thousand degrees Fahr. the speed could be somewhat less than that above stated, whereas if the blanks were not so highly heated a greater speed would be required.

In the operation of my apparatus a ring shaped blank, cast or forged, and at a soft forging temperature is placed centrally on the disk or table 10, and the latter is revolved at a high rate of speed. The blank is provided on its lower face with radial lugs 12 placed to conform to the grooves in the disk or table 10, for holding the blank in its proper position on the table, and is preferably provided with grooves on its upper surface in the vertical planes of the lugs 12 so that the cross sectional area of the blank will be no greater in the vertical planes of the lugs than it is at points intermediate the lugs, and by gradually widening the grooves in which the lugs rest, the portions of the blank in the vertical planes of the lugs will be free to expand or stretch equally with the parts of the blanks between the lugs. The blank revolves with the disk and the centrifugal force developed causes the hot, or semi-plastic blank to expand. The expansion of the blank reduces its cross sectional area, and the contact of the outer edge of the blank with the upwardly projecting peripheral flange 10^a of the disk, with the surface of said disk adjacent the peripheral flange, and with the under side of the cover 14, imparts final shape to the periphery of the blank, which in the present instance is shown as a tire 35 for a car wheel. This rapid rotation of the blank causes all the particles of the blank to fly outwardly from the centre thus stretching it until it reaches its final shape.

It is evident that many changes may be made in the form and construction of apparatus for imparting rotating motion to the blank and for holding the latter down on the revolving table, hence I would have it understood that I do not confine myself to the details shown but consider myself at

liberty to make such changes as may fall within the spirit of the invention.

Having fully described my invention what I claim as new and desire to secure by Letters-Patent, is:—

1. The method herein described of shaping metal parts consisting in forming a blank, heating it to a high temperature, placing the heated blank in a shaping device centrally with relation to the axis of said shaping device and rapidly rotating the latter and the blank. 65

2. The method herein described of shaping metal parts consisting in forming a ring shaped blank, heating it to a high temperature, placing it while hot within a shaping device centrally with relation to the axis of the latter, securing it against independent rotation and rapidly rotating the shaping device and the blank. 70 75

3. In apparatus for shaping metal blank by centrifugal action, the combination of a disk mounted to rotate and adapted to support a highly heated blank, the said disk being provided with a peripheral shaping member, and means for preventing independent rotation of the blank on the disk. 80

4. In apparatus for shaping a highly heated metal blank by centrifugal action, the combination of a disk mounted to rotate and provided with a peripheral shaping member, and with a top surface on which said blank is free to expand, and means for preventing independent rotation of the blank on the disk. 85 90

5. In apparatus for shaping metal blank by centrifugal action, the combination of a disk mounted to rotate and adapted to support a highly heated blank, and means for preventing independent rotation of the blank on the disk. 95

6. In apparatus for shaping metal blanks by centrifugal action, the combination of a table mounted to rotate and support a highly heated blank, the said table being provided with a peripheral shaping member, a cover detachably secured to the table and provided with a central opening and means for preventing independent rotation of a blank on the table. 100 105

In testimony whereof, I have signed this specification in the presence of two subscribing witnesses.

WILLIAM HENRY MORGAN.
